UNITED STATES PATENT OFFICE.

HYMAN GERTLER, OF MONTREAL, QUEBEC, CANADA, ASSIGNOR TO BENJAMIN LEVINSON, OF MONTREAL, CANADA.

BED-FRAME.

1,359,692.

Specification of Letters Patent. Patented Nov. 23, 1920.

Application filed March 18, 1920. Serial No. 366,790.

To all whom it may concern:

Be it known that I, HYMAN GERTLER, a subject of the King of Great Britain, and residing at 129 Colonial avenue, in the city 5 and district of Montreal, in the Province of Quebec, in the Dominion of Canada, have invented a new and useful Bed-Frame, of which the following is the specification.

The invention relates to bed frames, as described in the present specification and illustrated in the accompanying drawings that form part of the same.

The invention consists essentially in the novel means employed for connecting the 15 head and foot portions of the bed frame.

The objects of the invention are to eliminate the inconveniences incident to setting up and taking down bed frames; to reinforce the frame generally and thereby insure 20 a stiff frame when set up; and generally to provide a serviceable and durable frame with materially increasing the cost of production.

In the drawings, Figure 1 is a perspective 25 view of the bed frame set up.

Fig. 2 is a longitudinal sectional view through the side bar and fastenings.

Fig. 3 is a cross sectional view through a post and bracket, showing a transverse bar 30 broken away.

Fig. 4 is a perspective detail, showing a transverse bar and supporting bracket.

Fig. 5 is a perspective detail, showing the 35 end of a longitudinal side bar broken away to disclose the pin fastening.

Fig. 6 is a perspective detail, showing the bracket for the side and transverse bars as secured to a square end post.

Fig. 7 is a perspective view of the head 40 and foot portions of the bed frame assembled for storage.

Fig. 8 is an enlarged perspective detail of the connector for storage assembled.

Like numerals of reference indicate corresponding parts in each figure.

Referring to the drawings, 1 is a bracket secured to each of the bed posts and here shown as formed from a T-bar, which is cut away to form the base 2, which in Fig. 3, is 50 shown as curved in conformance with the shape of the bed post, and in Fig. 6 as flat in conformance with the shape of the bed post.

The central section of the T-bar extends 55 beyond the base 2 of the upper end of the latter, and is bent over to form the horizon-

tal portion 3 of the bracket, leaving the vertical portion 4 extending outwardly from the base, the latter having the lug 5, which is formed with the hook end 6, said lug projecting outwardly from the surface of the vertical portion toward the lower end thereof.

The horizontal portion 3 is formed with the pin hole 7 and is rigidly secured by the 65 rivet 8 or other fastening to the transverse bars 9 at the head and foot portions 10 and 11 respectively of the frame.

There are four of the brackets 1, each post having a bracket secured thereto and the 70 transverse bars 9 are preferably in the form of angle bars and in the case of a round bed post, the bars are split out, as shown at 12 in Fig. 3 and riveted to the base 2, though this is not necessary in the case of a square 75 bed post.

The longitudinal side bars 13 are joined at the ends by the rivets 14 to the brackets 15, said brackets having the pins 16 rigidly secured therein and extending through the 80 longitudinal side bars 13 and adapted to fit into the pin holes 7.

The brackets 15 extend inwardly at 17 and downwardly to form the leaf 18, said leaf having the slot 19 fitting on to the lug 5 behind the hook end 6. There are four brackets 15, one at each end of the longitudinal bars 13, said bars preferably being in angle form.

The connectors 20 are short lengths of 90 metal having the pins 21 at the ends which fit into the pin holes 7 and connect the head and foot portions for storage when the longitudinal side bars 13 have been removed.

What I claim is:

In a bed frame, having posts and connecting bars, secured to each post of the frame and formed of a short piece of T-bar having its central and vertical section bent over to form an angle bar, the horizontal portion 100 being rigidly secured to a connecting bar and having a pin hole therein and the vertical portion being formed with a key or lug in hook shape, longitudinal side bars, and brackets rigidly secured to said side bars at 105 the ends thereof, each having a projecting pin adapted to fit into said pin holes and a key slot hooking over said key or lug.

Signed at the city of Montreal, Province of Quebec, Dominion of Canada, this 12th 110 day of March, 1920.

HYMAN GERTLER.
